US0D1063958S

(12) **United States Design Patent** (10) **Patent No.:** **US D1,063,958 S**
(45) **Date of Patent:** **** Feb. 25, 2025**

(54) **DISPLAY SCREEN WITH GRAPHICAL USER INTERFACE**

(71) Applicant: **Airbnb, Inc.**, San Francisco, CA (US)

(72) Inventors: **Michelle Mederos**, San Francisco, CA (US); **Madelyn Taylor**, San Francisco, CA (US); **Daphne Jong**, San Francisco, CA (US); **Danielle Martin**, San Francisco, CA (US); **Eve Hu**, San Francisco, CA (US); **Esther Ouyang**, San Francisco, CA (US); **Randy Li**, San Francisco, CA (US); **Haoshan Zou**, San Francisco, CA (US); **Carlos Palacin Rubio**, San Francisco, CA (US)

(73) Assignee: **Airbnb, Inc.**, San Francisco, CA (US)

(**) Term: **15 Years**

(21) Appl. No.: **29/867,996**

(22) Filed: **Nov. 16, 2022**

(51) **LOC (15) Cl.** **14-04**

(52) **U.S. Cl.**

USPC **D14/485**

(58) **Field of Classification Search**

(57) **CLAIM**

The ornamental design for a display screen with graphical user interface as shown and described.

DESCRIPTION

The FIGURE is a front view of a display screen with graphical user interface showing our new design.

The peripheral dash-dot-dash lines illustrate a display screen or portion thereof and form no part of the claimed design. The remaining broken lines showing the graphical user interface form no part of the claimed design.

1 Claim, 1 Drawing Sheet
